CLAIM

The ornamental design for a baby canopy, as shown and described.

DESCRIPTION

FIG. 1 is a front perspective view of the baby canopy showing my new design;

FIG. 2 is another perspective view thereof, but with the zipper in the opened position;

FIG. 3 is a left front perspective view of FIG. 1, showing two pockets; and,

FIG. 4 is a top perspective view of FIG. 1.

The broken lines shown in FIG. 2 illustrate the interior of the baby canopy.

The remaining broken lines illustrate the zipper closure. None of the broken lines form part of the claimed design.
